This invention relates to a transistor circuit capable of delivering, independently of the load, an output current proportional to the difference between two voltages.

Such a circuit may in particular be used for remote measurements or controls. It comprises a comparator to which the said two voltages are applied and a compensator which receives a deviation signal from the comparator and returns a correcting signal to the comparator. A variable element delivers a voltage V_A which is measured in the comparator by comparing it with a reference voltage V_B . The comparator delivers a current proportional to the voltage difference $V_A - V_B$ and, from this current and by means of the compensator, a deviation current is obtained which is fed back to the input of the comparator for modifying the signal derived from V_A until the two signals applied to the comparator are identical. Such a circuit is known per se.

An object of the invention is to provide a transistor circuit of this kind which offers a high reliability in operation and satisfies severe operating conditions.

These conditions are, for example, in a special case envisaged as follows:

(1) The input on the side of the voltage to be measured (V_A) has a high impedance (from 30,000 to 40,000 ohms).

(2) The output of the compensator acts as a current injector, that is to say that the value of the output current must remain substantially unaffected by a variation in the resistance of the load (for example from 0 to 1,500 ohms). This is necessary because the installations, all of the same type, must be capable of operating irrespective of the distance, varying from one installation to another, between the assembly comprising the comparator and the compensator, which is situated at the place of measurement, and the measuring indicator arranged at a site which is more or less distant. It is furthermore possible to arrange several indicators in series and at different sites without the installation requiring any correction.

(3) It must be possible for the output current of the compensator to be positive or negative (according as V_A is greater or smaller than V_B), the output current varying for example from -5 ma. to +5 ma.

(4) The accuracy of the conversion into current for measurement is comparatively high and may be influenced by an increase in temperature (of the order of 1% from 0° C. to 45° C.; of the order of 5% from -20° C. to +55° C.).

The transistor circuit according to the present invention is characterized in that the compensator is fed with floating voltage under control of the said deviation signal, the output of the comparator being coupled to the common junction point of the bases of a p-n-p-type transistor and of an n-p-n-type transistor the emitter-collector paths of which are connected in series, which series-combination is connected to a direct-current source, and the common point of the two transistors being connected to a point of fixed potential with respect to the comparator.

Preferably, the voltage to be compared is applied to the base of a first transistor, the output of which is con-

nected to the base of a second transistor of the opposite conductivity type. The emitter of the first transistor is connected to the collector of the second transistor and to a common polarizing and load resistor.

5 In order that the invention may be readily carried into effect, it will now be described in detail, by way of example, with reference to the accompanying drawing showing diagrammatically one embodiment of the circuit according thereto.

10 The circuit shown substantially comprises the following parts:

A comparator K to which the difference between the voltages to be compared V_A and V_B is applied by means of members A and B;

15 A compensator C which receives the output voltage (deviation signal) from the comparator and returns to it a correcting signal comprising a proportional correcting current i which traverses a load resistor R_x and at least one measuring indicator I (milliammeter). The compensator is also coupled to a device D including a voltage source U.

The comparator K comprises, as is known per se, two transistors T_1 and T_2 connected in opposition, the emitters of which are connected to a resistor R_1 the other extremity of which is connected to a terminal -V of a source of supply voltage. The collector of transistor T_1 is connected to ground (that is to say to the positive supply terminal) whereas the collector of transistor T_2 is connected to the input of the compensator, the output of which is connected to the base of transistor T_1 via load resistor R_x and milliammeter I.

Since a high impedance source is being used, the voltages V_A and V_B must not give rise to appreciable currents. Voltages V_A and V_B are therefore applied to the bases of the transistors T_1 and T_2 by means of isolation devices A and B. The device B, which delivers only a reference voltage V_B , need comprise only one transistor T_3 , connected as an emitter follower. In this transistor, the voltage V_B is applied to the base, the collector is brought to the potential -V and the emitter is connected to earth through a load resistor R_2 and directly connected to the base of transistor T_2 . As regards the member A, this comprises two transistors T_4 and T_5 connected in cascade. The voltage V_A is applied to the base of the p-n-p-type transistor T_4 . Its collector is connected through a resistor R_4 to the supply voltage -V and directly to the base of the n-p-n-type transistor T_5 . The emitter of T_4 is connected to earth through resistor R_3 and directly to the collector of transistor T_5 which passes the output current of the device A through a resistor R_5 to the base of transistor T_1 . The passage of a comparatively large current through transistor T_4 is prevented by degenerative feedback between the collector of transistor T_5 and the emitter of transistor T_4 , and the temperature behaviour of T_4 remains approximately the same as that of T_3 . The emitter of transistor T_5 is connected through a resistor R_6 to the supply voltage -V.

60 In this way, the collector current of transistor T_5 is controlled by the collector current of transistor T_4 and the collector current of transistor T_5 supplements or aids the emitter current of transistor T_4 in supplying the said output current (which may vary in practice from -10 ma. upwards). The differential resistance of the junction between the emitter and the base of transistor T_4 thus varies only slightly because the latter does not deliver the relevant output current.

If a "reversible" current (varying from, for example, -5 ma. to +5 ma.) is desired at the output of the compensator, a classical circuit including two transistors T_6

and T_7 is preferably used, which transistors are of the p-n-p-type and n-p-n-type respectively.

In this circuit, one transistor is operative at a time, dependent upon the polarity of the current desired. The other transistor is cut off but would normally remain connected to a supply voltage U which may be comparatively high. In fact, in order to deliver +5 ma. on 1500 ohms, the supply voltage may in practice be of the order of 30 volts. Under these conditions, the blocked transistor is connected to an unduly high inverse voltage, resulting in the risk of damage to this transistor.

This difficulty is solved by supplying the compensator with a floating voltage controlled by the deviation signal. This can be achieved by coupling the output of the comparator K at the collector of transistor T_2 to the base electrodes of a PNP type transistor T_8 and an NPN type transistor T_9 . The emitter-collector paths of transistors T_8 and T_9 are connected in series across a direct current source of supply voltage U . The common junction point E of the emitter-collector paths of the transistors T_8 and T_9 are connected to a point of fixed potential, preferably ground. Since transistors T_8 and T_9 are of opposite conductivity types, the deviation signal applied to the base electrodes tends to simultaneously turn one transistor "off" while the other is turned "on." Depending upon which of these transistors is conductive, either the positive or negative terminal of the voltage source U is connected to ground through said conductive transistor.

The deviation signal is also applied to the base of transistor T_{10} via resistors R_7 and R_8 , thereby controlling the conduction thereof. The voltage drop across R_9 caused by the collector current of T_{10} turns on either transistor T_6 or T_8 , depending on the value of the deviation signal. In effect, the voltage of the source U is then applied to the series connection of either transistor T_6 or T_7 , whichever one is conductive, and the load resistor R_X , indicator I, and resistors R_5 and R_3 . The circuit is completed through ground and either T_8 or T_9 , whichever one is conducting. At the same time, the other transistor, T_7 or T_6 , which is cut-off, is protected against unduly high inverse voltages.

A portion of the deviation signal delivered by transistor T_2 is derived with the aid of a resistor R_7 in series with the input of the compensator circuit. To this end, R_8 is connected to one terminal of the source U and the common point of R_7 and R_8 is connected to the base of a transistor T_{10} . The collector-emitter path of transistor T_{10} is connected in series with a resistor R_9 the other end of which is connected to the other terminal of the source U . The common point of R_9 and T_{10} is connected to the bases of the transistors T_6 and T_7 . The collector-emitter paths of the transistors T_6 and T_7 are connected in series across the source U and the common point of their emitters is connected through the load resistor R_X and an indicator I to the base of transistor T_1 . Under these conditions, the deviation signal derived causes one of the transistors T_8 or T_9 to be conductive. Let it be assumed, for example, that the deviation signal increases. The transistor T_7 of the compensator circuit delivers more current and the transistor T_6 of the same circuit is subject to a higher inverse voltage. However, the signal derived tends to open the transistor T_8 and hence to decrease the inverse voltage of T_6 , and to cut off T_9 and hence to increase the supply voltage of transistor T_7 .

The values and types adopted for the various elements of the circuit now follow hereinafter as an example:

T_1, T_2, T_5, T_7, T_9 ----- OC 140 T.
 T_3, T_4 ----- OC 47.
 T_6, T_8, T_{10} ----- OC 77.
 R_1 ----- 1K ohm.
 R_2 ----- 5.6K ohms.
 R_3 ----- 600 ohms.
 R_4 ----- 3.34 ohms.

R_5 ----- 100 ohms.
 R_6 ----- 200 ohms.
 R_7 ----- 15K ohms.
 R_8 ----- 1K ohm.
 R_9 ----- 10K ohms.
 R_X ----- Variable (from 0 to 1,500 ohms).

It should be noted that it is advantageous to include a diode D_1 , for example of the type OA 85, in the connection between the emitter of transistor T_{10} and the corresponding terminal of the source U , the common point of D_1 and T_{10} being connected to the collector of transistor T_6 through a resistor R_{11} of 70 kilo ohms.

In the embodiment shown in the figure, the voltage V_B with which the voltage V_A is compared, may also be made variable. Both of these voltages are derived from a common source of A.C. voltage by means of a transformer T_r having a primary winding connected to this source and a tapped secondary winding. The tapped secondary winding is connected to ground. The transformer further includes a movable core N for varying the magnetic coupling between the primary and secondary windings. The alternating voltages produced between either end terminal winding and the ground tap are rectified by means of diodes D_2 and D_3 , filtered by means of capacitors Z_A and Z_B , and supplied to the base electrodes of transistors T_4 and T_3 , respectively. The core N may be made integral with a member whose displacement or position is to be measured.

Let us first assume that core N is positioned so that the voltage V_A is larger than the voltage V_B . Therefore, since V_A and V_B are both negative, $V_A - V_B < 0$. Under these conditions, the collector current of transistor T_2 is larger than the collector current of transistor T_1 and flows primarily from ground through the emitter base path of transistor T_3 to the collector T_2 . Transistor T_8 is thereby rendered conductive as well as transistors T_{10} and T_7 . A current path is now formed so that an output current flows from ground, through the emitter-collector path of T_8 , the voltage source U , the collector-emitter path of T_7 , the resistor R_X , the indicator I and the resistors R_5 and R_3 .

The output current stabilizes at a value

$$\frac{V_A - V_B}{R_5}$$

whereby the voltage difference $V_A - V_B$ which is effective between the base electrodes of the transistors T_1 and T_2 is exactly compensated by the voltage drop produced across the resistor R_5 by the output current flowing therein. If the core N is now displaced in a downward direction until V_B becomes equal to V_A , the collector current of T_2 is still sufficient to render T_8 conductive. The output or measuring circuit again follows the path as just described. In this case, the output or measuring current is equal to zero.

If the core N is displaced still further in the downward direction, V_B increases until V_A eventually becomes so much smaller than V_B that the collector current of T_2 becomes equal to the measuring current which now flows in the opposite direction through indicator I and resistors R_X , R_3 and R_5 . The collector current of transistor T_2 no longer supplies any current to the base of transistor T_8 . Transistors T_8 and T_9 are both cut-off, transistor T_{10} is also cut-off, as well as transistor T_7 . However, transistor T_6 is now conductive. The collector circuit of T_2 is now completed by the measuring circuit which follows the path from ground through resistors R_3 and R_5 , indicator I, resistor R_X , transistor T_6 , voltage source U , and resistors R_8 and R_7 to the collector of T_2 . If V_B increases still further, the collector current of T_2 eventually becomes so small that the base of transistor T_9 is driven in the forward direction by the voltage source U , via resistors R_8 and R_7 . The collector current of T_2 , if any, then flows through resistors R_7 and R_8 , source U , the collector-emitter path of transistor T_6 , resistor R_X , indicator

I and resistors R_5 and R_3 to ground. The measuring circuit now runs through resistors R_3 and R_5 , indicator I, resistor R_x , transistor T_6 and voltage source U as before, and from the positive terminal of source U to ground via transistor T_9 .

What is claimed is:

1. A circuit arrangement for supplying an output current to a load circuit which is proportional to the difference between first and second input voltages, said current being substantially independent of load impedance variations within predetermined limits, said circuit comprising comparison means having first and second input means and an output circuit for deriving a deviation signal, means for supplying said first and second voltages to said first and second input means, respectively, compensator means having an output circuit and an input circuit coupled to said comparison means output circuit and responsive to said deviation signal for producing an output current in said compensator means output circuit, means for connecting said load circuit in series between said compensator means output circuit and one of said input means thereby to supply a correction signal to said comparison means, means for supplying a floating supply voltage to said compensator means controlled by said deviation signal, said supplying means comprising a direct current source of supply voltage coupled to said compensator means, first and second transistors connected in series across said voltage source to provide a common emitter-collector path and a common junction therebetween and each having a control electrode, means for coupling said deviation signal from the output circuit of said comparison means to the control electrodes of said first and second transistors, and means for connecting the common junction in the said common emitter-collector path of said first and second transistors to a fixed potential.

2. Apparatus as described in claim 1 wherein said output current is substantially independent of load impedance variations in the range of zero to fifteen hundred ohms.

3. A circuit arrangement for supplying an output current to a load circuit which is proportional to the difference between first and second input voltages, said current being substantially independent of load impedance variations within predetermined limits, said circuit comprising comparison means comprising first and second transistors and first and second input means therefor, means for applying said first and second voltages to said first and second input means, respectively, said first transistor comprising an output electrode for deriving a deviation signal determined by the difference in said first and second voltages, compensator means having an output circuit and an input circuit coupled to said output electrode and responsive to said deviation signal for producing an output current in said compensator means output circuit, means for connecting said load circuit in series with said compensator means output circuit and one of said input means thereby to supply a correction signal to said comparison means, means for supplying a floating supply voltage to said compensator means controlled by said deviation signal, said supplying means comprising a direct current source of supply voltage coupled to said compensator means, third and fourth transistors of opposite conductivity type connected in series across said voltage source to provide a common emitter-collector path and a common junction therebetween and each having a control electrode, means for coupling said deviation signal from the output electrode of said comparison means to the control electrodes of said third and fourth transistors, and means for connecting the common junction in the said common emitter-collector path of said third and fourth transistors to ground.

4. Apparatus as described in claim 3 wherein one of said input means comprises fifth and sixth transistors of opposite conductivity type and having base, emitter and

collector electrodes, means for applying one of said input voltages to the base electrode of said fifth transistor, means connecting the collector electrode of said fifth transistor to the base electrode and said sixth transistor via fifth transistor thereby supplying a drive current thereto, and means connecting the emitter electrode of said fifth transistor to the collector electrode of said sixth transistor and to a common impedance element, and means for connecting a supply voltage to the emitter electrode of said sixth transistor so that collector current for said sixth transistor flows through said impedance element thereby providing a feedback voltage for stabilizing the operation of said fifth transistor.

5. Apparatus as described in claim 3 wherein said compensator means comprises fifth and sixth transistors of opposite conductivity type connected in series across said voltage source and in parallel with said third and fourth series connected transistors, the series connection of said fifth and sixth transistors providing a common emitter-collector current path for said fifth and sixth transistors and a common junction therebetween, and means for connecting said output circuit of said compensator means to the common junction in the said common emitter-collector path of said fifth and sixth transistors.

6. Apparatus as described in claim 5 wherein each of said fifth and sixth transistors include a base electrode and said compensator means further comprises a transistor amplifier having a control electrode and an output electrode, means for applying said deviation signal to said control electrode, and means coupling the output electrode of said amplifier to the base electrodes of said fifth and sixth transistors.

7. A circuit arrangement for supplying an output current to a load circuit which is proportional to the difference between first and second input voltages, said current being substantially independent of load impedance variations within predetermined limits, said circuit comprising comparison means comprising first and second transistors and first and second input means therefor, means for applying said first and second voltages to said first and second input means, respectively, said first transistor comprising an output electrode for deriving a deviation signal determined by the difference in said first and second voltages, said second transistor having a corresponding output electrode, means for connecting the corresponding electrode of said second transistor to ground, compensator means having an output terminal and an input circuit coupled to said first transistor output electrode and responsive to said deviation signal for producing an output current at said output terminal, means for connecting said load circuit in series between said output terminal and said second input means associated with said second transistor thereby to supply a correction signal to said comparison means, means for supplying a floating supply voltage to said compensator means controlled by said deviation signal, said supply means comprising a direct current source of supply voltage coupled to said compensator means, third and fourth transistors of opposite conductivity type connected in series across said voltage source to provide a common emitter-collector path and a common junction therebetween and each having a control electrode, means for coupling said deviation signal from the output electrode of said comparison means to the control electrodes of said third and fourth transistors, and means for connecting the common junction in the emitter-collector paths of said third and fourth transistors to ground.
